UNITED STATES PATENT OFFICE.

CLARENCE P. JOHNSON, OF NEWTON, MASSACHUSETTS.

COMMODITY-DISPLAY STAND.

Application filed November 19, 1924. Serial No. 750,956.

To all whom it may concern:

Be it known that I, CLARENCE P. JOHNSON, a citizen of the United States, and a resident of Newton, county of Middlesex, 5 and State of Massachusetts, have invented an Improvement in Commodity-Display Stands, of which the following description, in connection with the accompanying drawings, is a specification, like characters on the 10 drawings representing like parts.

My invention, which relates to commodity display stands and has among its objects the provision of a stand which may be taken apart and shipped in a substantially flat 15 package of minimum bulk, will be best understood from the following description when read in light of the accompanying drawings showing one specific embodiment of my invention selected for illustrative purposes, while the scope of my invention will 20 be more particularly pointed out in the appended claims.

In the drawings:—

Fig. 1 shows a perspective view of an assembled stand constructed according to my invention;

Fig. 2 is a transverse cross section of the stand according to Fig. 1;

Fig. 3 is a section on the line 3—3 of 30 Fig. 2;

Fig. 4 is a section on the line 4—4 of Fig. 2;

Figs. 5 and 6 respectively are sections on the lines 5—5 and 6—6 of Fig. 1; and

Fig. 7 shows a perspective of several sections which when assembled form the display stand according to Fig. 1.

Referring to the drawings showing the preferred embodiment of my invention I have shown a display stand comprising the lower tray or compartment 1 and the upper tray or compartment 3. The stand may be made of any suitable material and preferably is made of sheet metal, as for example 40 tin plate which may be painted and grained or otherwise finished to give the stand a pleasing appearance.

The lower tray comprises the end members 5 and 7, the front member 9, and the bottom member 11; while the upper tray comprises the end members 13 and 15, the front member 17, and the bottom member 19. As is clearly shown in the drawings the bottom members 11 and 19 of the trays are set at an 55 inclination to the front of the stand so as to hold the commodities, as for example

boxes of candy in tilted position, and thereby display the contents of the boxes, the front wall 17 of the upper tray being positioned rearwardly of the front wall 9 of the lower tray so that the upper tray does not obscure the contents of the lower tray.

The end members 5 and 7 at their lower edges are bent inwardly to form stiffening flanges 21 forming feet for the stand. As 65 shown in Figs. 6 and 7 the front edges of these members are bent inwardly to form flanges 23, which flanges are bent back towards the edges of the members as indicated at 25 so as to form outwardly opening 70 channels 27, while the end edges of the front member 9 are bent back as indicated at 29 to form flanges fitting into the channels 27. This construction locks the front member to the end members and permits them to be assembled or detached by sliding the front member vertically with relation to the end members. The front member 9 at its lower edge has the flange 30 similar to the flanges 21 on the end members. To further stiffen 80 the end members and to give a finish to the upper edge the front member is bent to form a flange 31 the ends of which engage the top edges 33 of the flanges 23 on the end members so as to insure that the upper edges of 85 the front end members will be in alignment at the corners of the tray.

The rearward vertical edges of the end members 7 are bent back on themselves to form a flange 35 which not only stiffens the 90 end members but receives the rearward edges of the end of the flange 37 formed on the ends of the bottom member 11. The bottom member 11 at its forward end is bent to form a horizontal portion 39 the front edge 95 of which has the upturned stiffening flange 41 which rests in the corner between the body of the front member 9 and its flange 30. The upper ends of the flanges 35 of the end members 7 and 9 are bevelled as indicated 100 at 43, and these ends in conjunction with the flanges 29 support the bottom members 11. The flanges 37 are provided with the slots 45 which receive bolts 47 passing through the end members, which bolts draw the end 105 members against the flanges 37 so as to support the bottom members 11 and add rigidity to the structure.

The bottom member 19 of the upper tray 3 is constructed similarly to the bottom member 11 of the lower tray, having the 110 downturned flanges 49, the horizontal por-

tion 51, and upturned flanges 53 at the front. The front member 17 of the upper tray is constructed similarly to the front member 9 of the lower tray, having the flanges 55 and 57 corresponding to the flanges 30 and 31 of the front member 9. As indicated in Fig. 3 the flange portions 49 of the bottom member 19, the bottom portions of the end members 13 and 15, and the upper portions of the end members 5 and 7 overlap. The upper edges of the end members 5 and 7 are bent back on each other as indicated at 59, the portion 59 being bent upwardly as indicated at 61 to form an upwardly opening channel which receives the flanges 49. After insertion of the flanges 49 the end members 13 and 15 are forced into the channels and act as wedges to secure the parts together.

20 It will be observed from Fig. 6 that the front member 17 of the upper tray is secured to the end members 13 and 15 in the same manner that the front member 9 of the lower tray is secured to the end members 5 and 7, the front member 17 for this purpose being formed with inturned flanges 63 which slide in the channels formed by the flanges 65 and 67 of the end members 13 and 15.

30 It will be observed that the bottom member 11 of the lower tray is parallel to the upper inclined edges of the end members 5 and 7, and that the upper tray is supported on the rearward portion of the top edges of the end members 5 and 7.

35 Although I have described for purposes of illustration one specific embodiment of my invention it is to be understood that I am not limited thereby to its particular mechanical details, but that within the scope 40 of my invention wide deviations may be made therefrom without departing from the spirit of my invention.

Claims—

1. A compactible commodity display stand, comprising when assembled a plurality of superimposed trays and formed of a plurality of substantially flat sheet metal sections for forming the bottoms and walls of said trays whereby when the stand is disjoined said sections may be shipped as a substantially flat package, said sections having edges bent to form U-shaped channels for detachably interlocking with adjacent

edges of said sections when said stand is assembled; said stand comprising a lower tray with a bottom wall inclined downwardly toward the front of said stand, and an upper tray the bottom of which is similarly inclined, the front of said upper tray being positioned rearwardly of the front of said lower tray, and the bottom and side walls of said upper tray being supported on the side walls of said lower tray.

2. A compactible commodity display stand, comprising a lower and an upper tray, said trays each having a bottom and end walls detachable from each other, the rearward portion of the upper edge of the sections forming the end walls of said lower tray being bent to form an upwardly opening channel, a section forming the bottom wall of said upper tray being at its ends bent downwardly to form a portion received in said channels, and the sections forming the end walls of said upper tray having their lower ends received in said channels and acting as wedges to retain said bottom wall in said channels, and said sections being substantially flat whereby said tray when disjointed may be shipped as a substantially flat package.

3. A commodity display stand comprising a pair of sheet metal end members, said members having vertical front and rear edges and top edges inclined upwardly from the front to the rear of said members, a front member of sheet material the ends of which are detachably interlocked with the front edges of said end members, a bottom member extending from one end member to the other and being substantially parallel to the top edges of said end members, a bottom member for an upper tray extending from one to the other of the rearward portions of the top edges of said end members, end members for said upper tray, a front member for said upper tray interlocked at its ends with the front ends of said end members for said upper tray, and said members being substantially flat sheets whereby said tray when disjointed may be shipped as a substantially flat package.

In testimony whereof, I have signed my name to this specification.

CLARENCE P. JOHNSON.
